TOY AIRPLANE DEVICE

Frederic A. Christiansen, New York, N. Y.,
assignor to Bertram Barr, New York,
N. Y.

Application July 18, 1936, Serial No. 91,369

9 Claims. (Cl. 272—31)

This invention relates to new and useful improvements in a toy airplane device.

The invention has for an object the construction of a toy airplane device which is characterized by a tower and a plurality of arms associated with the tower in a particular manner, and supporting airplanes—so that the airplanes may "loop-the-loop" as well as circle the tower.

Specifically, the invention contemplates particular mechanism for accomplishing various motions of the airplane.

It is an object of this invention to arrange a vertical hollow shaft rotatively supported in the tower and fixedly supporting a drum, to arrange an internal shaft rotative through the hollow shaft, to support the airplanes indirectly upon the internal shaft, and to provide an arrangement for rotating the drum and for holding the internal or hollow shaft to obtain the motions desired, and also to bring the device to a stop if so desired.

Another object of the invention is the construction of a device as mentioned which is simple and durable and which may be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:—

Fig. 1 is a plan view of a device constructed according to this invention.

Fig. 2 is a side elevational view of Fig. 1.

Fig. 3 is a fragmentary horizontal sectional view taken on the line 3—3 of Fig. 2.

Fig. 4 is a fragmentary vertical transverse sectional view of Fig. 2.

Fig. 5 is a horizontal sectional view taken on the line 5—5 of Fig. 4.

Fig. 6 is a sectional view taken on the line 6—6 of Fig. 4.

Fig. 7 is a fragmentary sectional view taken on the line 7—7 of Fig. 1.

Fig. 8 is a plan view similar to Fig. 1 but illustrating a modified construction.

Fig. 9 is a side elevational view of Fig. 8.

Fig. 10 is a transverse vertical sectional view showing another modified form of the invention.

Fig. 11 is a sectional view of another modified form of the invention.

Fig. 12 is a fragmentary horizontal sectional view taken on the line 12—12 of Fig. 11.

The toy airplane device, according to this invention, comprises a hollow tower 10 in which a vertical hollow shaft 11 is rotatively supported. This vertical hollow shaft 11 consists of a bottom section 11^b and a top section 11^a which extend from the top of the tower 10. These sections 11^a and 11^b are fixedly connected together by welding. A drum 12 is coaxially fixed on the upper end of the top section 11^a. An internal shaft 13 is rotatively supported in the hollow shaft 11 and extends from the top end thereof. A support 14 is rotatively mounted on the extended portion of the internal shaft 13 and is connected with a gear 15 which meshes with gear teeth 16 formed on one edge of the drum 12.

An element 17 is associated with one of the shafts and frictionally cooperates with the other of the shafts to maintain the shafts in frictional engagement with each other when desired. A motor 18 is supported on a bracket 19 which is attached on the tower 10. This motor is provided with a pinion 20 which meshes with gear teeth 21 formed on the other edge of the drum 12.

A radial arm 22 projects from the support 14 and is adapted to support an airplane 23. This radial arm has a longitudinal inner end portion 22^a which continues into a transverse intermediate portion 22^b which in continues into a longitudinal outer end portion 22^c. The airplane 23 is attached upon the outer end portion 22^c. The connection between the airplane and the radial arm is such that the airplane may bank one way or the other, and may also tilt upwards or downwards. This is accomplished by the arm portion 22^c swivelly engaging into a lug 24 of a bracket 25 which is provided with a trunnion 26, the elements of which are at right angles to the arm portion 22^c. The body of the airplane is formed with a hollow 23' in which the bracket 25 is disposed. It should be noted that the airplane 23 may turn about the rod portion 22^c as a pivot as well as around the trunnion 26 as a pivot which is at right angles to the turning permitted by the arm portion 22^c.

A brake is associated with the internal shaft 13 for holding this shaft when desired. This brake comprises a rod 27 extending radially from the tower and provided with a handle 28 at its outer end by which it may be moved. This rod is slidably supported and at its inner end is provided with a brake shoe 29 adapted to engage against a pulley 30 which is fixed upon the shaft 13. Thus, the handle 28 may be moved to engage the brake shoe 29 against the pulley to hold the internal shaft.

55

The hollow tower 10 includes a hollow pedestal portion 10a to which a hollow tubular portion 10b is connected. A substantially spherical portion 10c is mounted upon the upper portion 10b and encases the motor 18, the drum 12 and the other parts in this vicinity. A bracket 33 projects from the upper end of the internal shaft 13 and supports a ball 34 upon which a flag or pennant 35 is mounted. A shell shaped cover 36 is supported 10 on the ball 35 and cooperates with the spherical portion 10c of the tower to encase the operative mechanism of the device.

The drum 12 is formed with a transverse partition 12a which has a hub portion engaging the upper end of the hollow shaft 11. Several screws 12b serve to fixedly attach the hub portion of the drum with the hollow shaft. Several thrust bearings 38 are interposed between the internal shaft 13 and the hollow shaft 11 for rotatively connecting these shafts together. The support member 14 is provided with an arm 39 extending in the opposite direction to the arm 22. A counterweight 40 is mounted upon the end of the arm 39 and is for the purpose of counterweighting the airplane 23. A brake is provided for stopping rotations of the hollow shaft 11 and comprises a brake drum 41 fixed upon the bottom end of the hollow shaft 11 and cooperative with a brake shoe 42 mounted upon the rod 27 but diametrically opposite to the brake shoe 29. Thus, the rod 27 may be moved in one direction for applying one brake, or in the other direction for applying the other brake.

The operation of the device is as follows:

35 Rotations from the motor 18 will be transmitted to rotate the drum 12 and thus the hollow shaft 11. The friction element 17 will cause the internal shaft 13 to rotate along with the hollow shaft 11 and consequently the support 14 will 40 turn around the tower as a center. Thus, the airplane 23 is carried around the tower. The brake 29 may be applied partially or completely. If partially applied the internal shaft 13 will turn at a different rate than the hollow shaft 11, 45 and a portion of the rotations of the drum 12 will be transmitted to turn the gear 15 and rotate the support 14. The airplane 23 will then loop-the-loop in addition to its motion around the tower. If the brake is completely applied the 50 airplane will merely loop-the-loop. The dot and dash lines in Fig. 2 illustrate another position of the airplane during the looping action. If the brake 42 is applied the entire device is brought to a stop. Of course, the motor 18 must be cut.

55 In Figs. 8 and 9 a modified form of the invention has been disclosed which distinguishes from the prior form merely in the construction of the brake. In this form of the invention a frame 50 is mounted on the ground and connected with 60 the side of the pedestal portion 10a of the tower. The rod 27 is slidable in this frame. A lever 28a is pivotally mounted at its bottom end 28aa upon the frame 50 and the rod 27 has a bent end 27a connected intermediate of the lever 28a. Thus, 65 the lever may be pivoted in one direction or the other to apply the brakes.

In Fig. 10 another form of the invention has 70 been disclosed which distinguishes from the prior form in several respects. The auxiliary arm 39' supports a counterweight 40' for the airplane. This counterweight is threadedly associated with the rod 39' so that it may be adjusted to various positions to compensate for loads carried by the airplane. Furthermore, in this device a rheostat 75 51 is provided for the purpose of controlling the

speed of the motor 18. The wiring is not illustrated on the drawings since it forms no part of the invention. A further variation resides in the fact that merely the internal shaft 13 is provided with the brake 29, 30. In other respects this form of the invention is identical to the previous form and similar parts may be recognized by the same reference numerals.

In the form of the invention illustrated in Figs. 11 and 12 the toy airplane device comprises a 10 hollow tubular tower 60 supported on a hollow pedestal 61 and at the top end supporting a hollow spherical member 62. A hollow shaft 63 is rotative through the tower 60. An internal shaft 64 is rotative through the hollow shaft 63. A support member 65 is fixed on the extended end of the internal shaft. A loop-the-loop airplane mechanism 66 is rotatively mounted on the support member 65. A drive is provided for the loop-the-loop airplane mechanism and essentially comprises a driver wheel 67 fixed on the hollow tubular shaft 63 and driving a wheel 68 connected with an arm 69 which supports the airplane 66'. A flanged wheel 70 is mounted upon the bottom end of the hollow shaft 64. A brake 25 wheel 71 is mounted on the lower end of the internal shaft 64.

A motor 72 is movably supported and has a drive pinion 73 engageable against the flanges of the said flanged wheel 70. A mechanism is 30 provided for manually moving said motor which includes a rod 74 associated with resilient elements 75 and 84 which in turn are associated with the motor 72. A brake 76 is associated with the resilient elements 75 and 84 and is engageable 35 against said brake wheel 71.

The support member 65 is formed with a horizontal bearing portion through which a portion 69' of the rod 69 passes. The rod 69 continues from one end of the portion 69'. From the 40 other end there is an extension 69a. A weight 70 is adjustably mounted upon the extension 69a and is for the purpose of counterbalancing the arm 69 and the airplane 66'. A trailer rod 71' is attached intermediate of the ends of the 45 rod 69. A bearing 78 is mounted upon the inner wall at the top of the spherical member 62 and serves to assist in rotatively supporting the support member 65.

The flanged wheel 70 has flanges 70a and 70b. 50 The pinion 73 engages between these flanges. The pinion 73 is driven by a gear system 79 connected with the motor 72. A bracket 80 is attached upon the side wall of the motor 72. The motor is pivotally supported by a pintle 81 on a 55 bracket 82 mounted upon the pedestal 61. A rod 83 is slidably through the bracket 80. Coaxial springs 84 and 75 are mounted upon the rod 83. A universal joint 85 connects the rod 83 with the rod 74. A handle 88 is arranged on the end of 60 the rod 74 by which it may be moved.

The operation of the device is as follows:—

The handle 88 may be moved in one direction or the other to cause the device to operate in various manners. For example, when the handle 88 is moved towards the right the motor 72 will 65 pivot so that the drive pinion 73 engages the flange 70a. This will cause the hollow shaft 63 to rotate in one direction. The internal shaft 64 frictionally engages the hollow shaft 63 and rotates with it. Consequently, the support 65 rotates and the airplane 66' travels in a circle about the tower. The hollow spherical top 62 has a rotative top section 62' which rotates along 70 with the support member 65.

When the handle 88 is pulled further to the right the rod 83 will be moved against the restraining action of the springs 15 and 84 and soon one of the brakes 76 will engage the wheel 71. Then the internal shaft 64 is reduced in speed or completely fixedly held. Since the support member 65 is connected with the internal shaft 64 it will be reduced in speed or held, consequently the drive disc 67 which is moving 10 along with the hollow shaft 63 will now rotate the disc 68 and cause the arm 69 to rotate and loop-the-loop the airplane 66'. When the handle 80 is moved towards the left the motor 62 will pivot so that the drive pinion 73 engages the 15 flange 70^b. The device will now be rotating in the opposite direction. When the brake 76 re-engages the brake wheel 71 the airplane will be caused to loop-the-loop.

While I have illustrated and described the preferred embodiments of my invention, it is to be understood that I do not limit myself to the precise constructions herein disclosed and the right is reserved to all changes and modifications coming within the scope of the invention as defined 25 in the appended claims.

Having thus described my invention, what I claim as new, and desire to secure by United States Letters Patent is:—

1. A toy airplane, comprising a hollow tower, 30 a vertical hollow shaft rotatively supported in said tower, a drum coaxially fixed on the upper end of said hollow shaft, an internal shaft rotatively supported in said hollow shaft and extending from the top thereof, a support member 35 rotatively mounted on the extended portion of said internal shaft and connected with a gear meshing with gear teeth on said drum, an element causing frictional engagement of said shafts, a motor driving said drum, a radial arm projecting from said support member for supporting an airplane, and a brake for holding said internal shaft against rotation.

2. A toy airplane, comprising a hollow tower, 45 a vertical hollow shaft rotatively supported in said tower, a drum coaxially fixed on the upper end of said hollow shaft, an internal shaft rotatively supported in said hollow shaft and extending from the top thereof, a support member rotatively mounted on the extended portion of 50 said internal shaft and connected with a gear meshing with gear teeth on said drum, an element causing frictional engagement of said shafts, a motor driving said drum, a radial arm projecting from said support member for supporting an airplane, and a brake for holding said 55 internal shaft against rotation, and thrust bearings being arranged between the internal shafts.

3. A toy airplane, comprising a hollow tower, 60 a vertical hollow shaft rotatively supported in said tower, a drum coaxially fixed on the upper end of said hollow shaft, an internal shaft rotatively supported in said hollow shaft and extending from the top thereof, a support member rotatively mounted on the extended portion of 65 said internal shaft and connected with a gear meshing with gear teeth on said drum, an element causing frictional engagement of said shafts, a motor driving said drum, a radial arm projecting from said support member for supporting 70 an airplane, and a brake for holding said internal shaft against rotation, said support member being provided with radially extending arms, an airplane being mounted upon one of the arms 75 and counterweight on the other, and a universal

connection being arranged between the airplane and the support arm.

4. A toy airplane, comprising a hollow tower, 5 a vertical hollow shaft rotatively supported in said tower, a drum coaxially fixed on the upper end of said hollow shaft an internal shaft rotatively supported in said hollow shaft and extending from the top thereof, a support member 10 rotatively mounted on the extended portion of said internal shaft and connected with a gear meshing with gear teeth on said drum, an element causing frictional engagement of said shafts, a motor driving said drum, a radial arm projecting from said support member for supporting 15 an airplane, a brake for holding said internal shaft against rotation, and a brake for holding said hollow shaft.

5. A toy airplane comprising a hollow tower, a vertical hollow shaft rotatively supported in said tower, a drum coaxially fixed on the upper end of 20 said hollow shaft, an internal shaft rotatively supported in said hollow shaft, and extending from the top thereof, a support member rotatively mounted on the extended portion of said internal shaft and connected with a gear meshing 25 with gear teeth on said drum, an element causing frictional engagement of said shafts, a motor driving said drum, a radial arm projecting from said support member for supporting an airplane, and a brake for holding said internal shaft 30 against rotation, said tower including a hollow pedestal, a tubular intermediate portion, and a hollow spherical top portion encasing the drum and other parts of the device.

6. A toy airplane comprising a hollow tower, 35 a vertical hollow shaft rotatively supported in said tower, a drum coaxially fixed on the upper end of said hollow shaft, an internal shaft rotatively supported in said hollow shaft and extending from the top thereof, a support member 40 rotatively mounted on the extended portion of said internal shaft and connected with a gear meshing with gear teeth on said drum, an element causing frictional engagement of said shafts, a motor driving said drum, a radial arm 45 projecting from said support member for supporting an airplane, and a brake for holding said internal shaft against rotation, comprising a 50 brake drum fixed on the shaft, a rod slidably mounted and provided with a brake shoe engageable against the brake drum, and an element by which the rod may be moved.

7. A toy airplane comprising a hollow tower, a hollow shaft rotative through said tower, an internal shaft rotative through said hollow shaft, 55 a support member fixed on an extended end of said internal shaft, a loop-the-loop airplane mechanism rotatively mounted on said support member, a drive for said loop-the-loop airplane mechanism connected with said internal shaft, a 60 flanged wheel on said hollow shaft, a brake wheel on the other end of said internal shaft, a motor movably supported and having a drive pinion engageable against the flanges of said flanged wheel, a mechanism for manually moving said 65 motor including a resilient element, and a brake associated with said resilient element and engageable with said brake wheel.

8. A toy airplane comprising a hollow tower, 70 a hollow shaft rotative through said tower, an internal shaft rotative through said hollow shaft, a support member fixed on an extended end of said internal shaft, a loop-the-loop airplane mechanism rotatively mounted on said support member, a drive for said loop-the-loop airplane 75

- mechanism connected with said internal shaft, a flanged wheel on said hollow shaft, a brake wheel on the other end of said internal shaft, a motor movably supported and having a drive pinion engageable against the flanges of said flanged wheel, a mechanism for manually moving said motor including a resilient element, and a brake associated with said resilient element and engageable with said brake wheel, and comprising a pair of 5
brake shoes arranged on opposite sides of said brake wheel, an operator rod connected with said brake shoes and constituting an operator for said mechanism for manually moving the motor, whereby when the rod is moved in one direction 10
15 one of the brake shoes engages the brake wheel, and when moved in the other direction the other brake shoe engages the brake wheel.

9. A toy aeroplane, comprising a hollow tower, a vertical hollow shaft rotatively supported in

said tower, a drum coaxially fixed on the upper end of said hollow shaft and having gear teeth thereon, an internal shaft rotatively supported in said hollow shaft and having a portion extending from the top thereof, a support member 5
rotative on said extended end and connected with a gear meshing with said gear teeth, a source of power adapted to rotate said drum, a pair of diametrically opposite radially extending arms, projecting from said support member, an aeroplane mounted on one of said arms, a brake mechanism adapted to retard the rotating motion of 10
said inner shaft to permit said aeroplane to loop-the-loop, and a weight on the other of said arms to counterbalance the weight of said aeroplane so as to require less force to make said aeroplane loop-the-loop. 15

FREDERIC A. CHRISTIANSEN.
